UNITED STATES PATENT OFFICE.

EBENEZER N. SLOCUM, OF FORT SMITH, ARKANSAS, ASSIGNOR OF TWO-THIRDS TO HENRY H. HOOVER, OF SAME PLACE.

LOCOMOTIVE-EXHAUST.

SPECIFICATION forming part of Letters Patent No. 652,902, dated July 3, 1900.

Application filed August 18, 1899. Serial No. 727,657. (No model.)

To all whom it may concern:

Be it known that I, EBENEZER N. SLOCUM, of Fort Smith, in the county of Sebastian and State of Arkansas, have invented a new and 5 Improved Locomotive-Exhaust, of which the following is a full, clear, and exact description.

The objects of the invention are to provide a new and improved locomotive-exhaust arranged to insure a free escape of the exhaust steam from the engine-cylinders without danger of creating back pressure therein and to provide a perfectly-balanced non-pulsating draft in the fire-box and smoke-flues with a reduced consumption of fuel and with the cinders put out and rendered harmless before escaping from the stack.

The invention consists of novel features and parts and combinations of the same, as will be fully described hereinafter and then pointed out in the claim.

A practical embodiment of my invention is represented in the accompanying drawings, forming a part of this specification, in which 25 similar characters of reference indicate corresponding parts in both the views.

Figure 1 is a longitudinal sectional elevation of the improvement as applied. Fig. 2 is a transverse section of the same on the line 30 2 2 in Fig. 1.

In locomotives as heretofore constructed the distance between the tip of the exhaust-nozzle and the base of the stack was such that the exhaust-steam was discharged into 35 the smoke-box above the lowermost flues, so that the steam traveled up a short distance to the base end of the petticoat or draft pipe leading to the stack, and in order to create the desired draft in the flues or 40 smoke-box it was necessary to let the exhaust-steam issue from the nozzle with very great force, and in order to obtain this force the nozzle has to be constricted to such an extent that it causes back pressure in the cylinders, 45 and as the steam forcibly pulsated in the smoke-box it created violent pulsating drafts in the smoke-flues and fire-box, and consequently an uneven burning of the fuel and a waste thereof. In order to avoid all this, I 50 increase the distance from the base of the draft-pipe or stack to the tip of the nozzle,

preferably by shortening the nozzle and by elongating the smoke-box vertically or in remodeling old work by elongating the upper end of the smoke-box and leaving the nozzle 55 the same length as at present or shortening it to a slight extent, so that it requires considerable time for the now unrestrained steam to travel from the nozzle to the stack to produce a non-pulsating even draft on the burning fuel in the fire-box. By bringing the top of the nozzle below the lowermost smoke-flues of the boiler the exhaust-steam traverses the entire discharge area of the smoke-flues, so that the cinders passing into the smoke-box 65 from the flues are subjected to the action of the steam and are thus readily put out and rendered harmless by the time they pass out of the stack.

As shown in the drawings, the locomotive-boiler is provided with the usual shell A, in which extend the smoke-flues B, discharging the smoke, gases, and cinders from the fire-box into a smoke-box C, preferably elongated vertically below the shell A and above the 75 same, as is plainly indicated in Figs. 1 and 2. The lower extension of the smoke-box C is formed in its bottom with an exhaust-port of large diameter, and over such port is arranged an exhaust-nozzle D, which is wide 80 and short, as shown, located directly opposite the base of the smoke-stack E, leading from the top of the smoke-box and carrying the smoke and cinders to the outside.

By the arrangement described the tip of 85 the exhaust-nozzle D is below the horizontal plane of the discharge from the lowermost smoke-flues B, and the discharge between said tip and the base of the stack E is immensely increased over that usually given in 90 locomotives heretofore constructed. The nozzle D itself may be increased to insure a free and untrammelled issuing of the exhaust-steam into the smoke-box, so that when the locomotive is in operation the steam can rise 95 in a continuous column in the smoke-box and pass into the stack E without creating a violent pulsating draft in the smoke-flues B and the fire-box, but, on the contrary, producing a non-pulsating even draft in said smoke-flues and fire-box. Furthermore, the steam while passing the long distance between the

tip of the nozzle D and the base of the stack A traverses the entire discharge area of the smoke-flues B, and consequently the steam acts on the hot burning cinders and readily 5 extinguishes them, so that they are harmless before leaving the stack E.

If desired, an angularly-disposed netting F may be arranged in the smoke-box C, extending from the flue-sheet above the uppermost flues B downward and forward to the exhaust-nozzle, to prevent the heavy cinders from passing to that portion of the smoke-box containing the exhaust-nozzle.

Having thus fully described my invention, 15 I claim as new and desire to secure by Letters Patent—

In a locomotive, a boiler-shell, a smoke-box

connected with the front of the boiler-shell and having an extension both above and below the same, a stack rising from the top of 20 the upper extension of said smoke-box, there being provided an exhaust-port of large diameter in the bottom of the lower extension of the smoke-box, and a short and wide exhaust-nozzle secured in the bottom of the 25 lower extension of the smoke-box over the port directly opposite and pointing toward the stack and whose tip is below the discharge of the lowermost flue in the boiler-shell, as and for the purpose set forth.

EBENEZER N. SLOCUM.
